UNITED STATES PATENT OFFICE.

MARTIN T. GLYNN, OF BOSTON, MASSACHUSETTS.

DESIGN FOR A DOOR-FENDER PLATE.

SPECIFICATION forming part of Design No. 34,217, dated March 12, 1901.

Application filed February 18, 1901. Serial No. 47,881. Term of patent 7 years.

To all whom it may concern:

Be it known that I, MARTIN T. GLYNN, of Boston, in the county of Suffolk and State of Massachusetts, have invented a new and useful Design for a Door-Fender Plate, of which the following, taken in connection with the accompanying drawings, is a specification.

Figure 1 is a plan view of a door-fender plate. Fig. 2 is an end view of the same looking from the top.

As shown in the drawings, the leading or material features of my design consist of the segment-shaped pieces cut out, the parts cut out arranged symmetrically, as shown, and relieved by curved beads B B.

The design also has openings bounded by

straight lines and curves, as shown, near the lower end of the fender.

Having described my invention, what I claim as new, and desire to secure by Letters Patent, is—

The design for a door-fender plate, as herein shown and described.

In testimony whereof I have signed my name to this specification, in the presence of two subscribing witnesses, on this 15th day of February, A. D. 1901.

MARTIN T. GLYNN.

Witnesses:

FRANK G. PARKER,
JOHN BUCKLER.
